UNITED STATES PATENT OFFICE.

CARL D. MILLER, OF KANSAS CITY, MISSOURI.

GRINDER.

1,284,127.

Specification of Letters Patent.

Patented Nov. 5, 1918.

Application filed March 16, 1918. Serial No. 222,910.

To all whom it may concern:

Be it known that I, CARL D. MILLER, a citizen of the United States, residing at Kansas City, in the county of Jackson and 5 State of Missouri, have invented a new and useful Grinder, of which the following is a specification.

The device forming the subject matter of this application is adapted to be employed 10 for grinding the valves of internal combustion engines, and the invention aims to provide novel means whereby an oscillating movement and a progressive rotary movement may be imparted to the valve, as the 15 valve is rotated on its seat, to effect the grinding operation.

Another object of the invention is to provide novel means whereby a chamber is formed for the reception of the mechanism 20 which connects the motor with the grinding shaft.

It is within the province of the disclosure to improve generally and to enhance the utility of devices of that type to which the 25 present invention appertains.

With the foregoing and other objects in view, which will appear as the description proceeds, the invention resides in the combination and arrangement of parts and in 30 the details of construction hereinafter described and claimed, it being understood that changes in the precise embodiment of the invention herein disclosed can be made within the scope of what is claimed without 35 departing from the spirit of the invention.

In the accompanying drawings:—

Figure 1 shows in longitudinal section, a valve grinder constructed in accordance with the present invention, the same being 40 shown in operative relation to the valve to be ground, and parts being left in elevation;

Fig. 2 is a cross section taken approximately on the line 2—2 of Fig. 1; and

Fig. 3 is a fragmental elevation showing 45 a portion of the grinding shaft.

In carrying out the invention there is provided a casing 1 which may be made of aluminum or any suitable material, the casing being of tubular form and including 50 a reduced neck 2 in which is mounted a switch 3 of any desired form, in circuit with a conductor 4. The casing 1 is supplied with an internal shoulder 5 against which abuts a transverse platform 6 carrying two posts 7 constituting a part of, or 55 supporting an electrical motor 8 supplied

with current from the conductor 4 and controlled by the switch 3. The armature shaft of the motor 8 is denoted by the numeral 9.

A cap 10 is threaded on the casing 1 and 60 has a forwardly projecting boss 11 within which is located a bearing bushing 12. A ring 14 is interposed between the cap 10 and the platform 6 and is bound closely against the platform and the cap when the 65 cap is threaded on the casing 1. The construction is such that a chamber 15 is fashioned within the ring 14 and between the platform 6 and the end of the cap 10, this chamber being fluid tight so as to receive 70 a grease or lubricant in which sundry parts hereinafter described operate.

A grinding shaft 16 is journaled for rotation in the bushing 12 and is provided with a bit 17 of any desired type, adapted 75 to coact with a valve 18, to rotate the valve on a seat 19 formed in a cylinder 20, the object in view being to effect a grinding of the valve in a well-known manner. A stub shaft 21 is journaled in the platform 6 and 80 has a socket 22 of rectangular cross section, the socket receiving the armature shaft 9, the armature shaft and the inner end of the stub shaft 21 being connected by a cross pin 23. The construction is such that a 85 secure driving connection between the armature shaft 9 and the stub shaft 21 is afforded, the stub shaft always being rotated when the armature shaft is rotated. The forward end of the stub shaft 21 may 90 be pointed as shown at 24 and is received for rotation in a recess 25 formed in the butt end of the grinding shaft 16. The stub shaft 21 passes through a washer 26 held against the platform 6 by the rear end 95 of the shaft 16, the washer carrying a packing 27 adapted to prevent the oil in the chamber 15 from working backwardly into the compartment which contains the motor 8. A pinion 28 is fashioned in the stub 100 shaft 21. A disk 29 is rotatably mounted on the shaft 16 and is held in abutment with the rear face of the end wall of the cap 10 by means of a flange 31 on the shaft 16, the disk including a counterpoise 30. The 105 disk 29 carries a stub shaft 32 on which is mounted a gear wheel 33 meshing into the pinion 28 and operating in a slot 40, fashioned in the side of the shaft 16 and elongated circumferentially of the shaft. 110 The gear wheel 33 carries a pivot element 34 on which is mounted one end of a link

35 pivoted on a stud 36 constituting a part of an arm 37 carried by the grinding shaft 16.

An oscillating movement is imparted to the grinding shaft 16 and consequently to the valve 18 by a mechanism embodying the motor 8, the armature shaft 9, the stub shaft 21, the pinion 28, the link 35 and the arm 37, the disk 29 remaining fixed against rotation. When the pivot elements 34 and 36 approach the line of centers of the stub shaft 21 and the stub shaft 32, the leverage on the disk 29 is increased, compared with the leverage on the shaft 16. Then, for a time, the disk 29 is rotated, the shaft 16 being rotated, thus to impart an advancing rotary movement to the valve 18. As the disk 29 is rotated, as aforesaid, the pivot elements 34 and 36 are moved off the straight line connecting the stub shaft 32 and the stub shaft 21, whereupon the leverage upon the shaft 16 becomes greater than the leverage upon the disk 29, the rotation of the latter ceasing, and the pinion 33 being rotated on the disk 29 to cause the oscillation of the shaft 16 and the valve 18 as above described.

Having thus described the invention, what is claimed is:—

1. In a valve grinder, a support; a grinding shaft journaled therein and provided with a laterally extended arm; a disk mounted to rotate on the shaft and supplied with a counter-weight located in a common plane

with the disk; a gear wheel journaled on the disk in eccentric position with respect to the center of rotation on the disk; a driving pinion meshing into the gear wheel and supported for rotation independently of the disk; and a link having its ends pivoted, respectively, to the gear wheel and to the arm. 35 40

2. In a valve grinder, a casing having an internal shoulder; a removable platform abutting against the shoulder and forming a rear compartment in the casing; a cap mounted on the casing; a ring open at both ends and disposed between the cap and the platform, and bound against the platform by the cap, to hold the platform on the shoulder, the cap, the ring and the platform defining an oil compartment; a motor in the rear compartment; means for connecting the motor with the platform, whereby the motor and the platform may be removed together; and a shaft independent of said means, the shaft passing through the platform; a grinding shaft journaled in the cap; and an operative connection between the shafts, said connection being located in the oil compartment. 45 50 55

In testimony that I claim the foregoing as my own, I have hereto affixed my signature in the presence of two witnesses.

CARL D. MILLER.
